CLAIM

The ornamental design for a court lamp, as shown and described.

DESCRIPTION

FIG. 1 is a front, right, top perspective view of a court lamp showing our new design;

FIG. 2 is a back, left, bottom perspective view thereof;

FIG. 3 is a front view thereof;

FIG. 4 is a back view thereof;

FIG. 5 is a left view thereof;

FIG. 6 is a right view thereof;

FIG. 7 is an enlarged top view thereof;

FIG. 8 is an enlarged bottom view thereof;

FIG. 9 is an enlarged view of the encircled area 9 of FIG. 1;

FIG. 10 is an enlarged view of the encircled area 10 of FIG. 2; and,

FIG. 11 is an enlarged view of the encircled area 11 of FIG. 6.

The broken lines shown on the drawings depict portions of the court lamp that form no part of the claimed design.
